R. A. SCHOENBERG.

NOW BY JUDICIAL CHANGE OF NAME R. A. BELMONT.

REFILLABLE PLUG.

APPLICATION FILED, JUNE 18, 1917.

1,265,391.

Patented May 7, 1918.

UNITED STATES PATENT OFFICE.

RALPH A. SCHOENBERG, (NOW BY JUDICIAL CHANGE OF NAME RALPH A. BELMONT,) OF NEW YORK, N. Y.
REFILLABLE PLUG.

1,265,391.

Specification of Letters Patent.

Patented May 7, 1918.

Application filed June 18, 1917. Serial No. 175,250.

To all whom it may concern:

Be it known that I, RALPH A. SCHOENBERG, (now by judicial change of name RALPH A. BELMONT,) of New York, in the county and State of New York, have invented new and useful Improvements in a Refillable Plug, of which the following is a specification.

My invention is in part an improvement 10 of the device of my patent issued May 1, 1917, No. 1,224,505 in which I show a metal shell with a fiber lining and insulating washers for the center contact and my present invention contemplates adaptation to a refillable fuse plug so that a great saving of material by reason of the fact that only the fuse wire needs be thrown away.

A feature of my invention is a removable cap to give access to the interior of the plug.

Another feature is a center contact adjustable for the application of a new fuse wire.

Another feature is a hole in the center contact for passage of the fuse wire.

Another feature is a barrier to insulate 25 the fuse wire.

Another feature is that the screw shell carries a screw contact.

Another feature is a collar for use in holding the cap or cover in position.

Another feature is the lightness of the structure which is particularly important in shipping and in connection with customs of foreign countries where duty is charged by weight.

Other features will be pointed out below. In the drawings:

Figure 1 is a central longitudinal sectional view of a fuse plug embodying my invention;

Fig. 2 is a plan of the innermost washer;

Fig. 3 is an end elevation of the screw shell;

Fig. 4 is a plan view of the intermediate washer;

Fig. 5 is a section on line 5—5 of Fig. 6;

Fig. 6 is a section on line 6—6 of Fig. 1;

Fig. 7 is a plan view of the outer washer;

Fig. 8 is a plan view of the metal staple forming part of the center contact showing 50 the same in its condition before clenching;

Fig. 9 is a section on line 9—9 of Fig. 1;

Fig. 10 is a plan view of the supplemental washer;

Fig. 11 is a section on line 11—11 of 55 Fig. 1;

Fig. 12 is a modification; and
Fig. 13 shows another form of center contact.

The body of the fuse plug is hollow and consists of a threaded metallic shell A with 60 an annular shoulder a and an outturned flange at its outer end and an inturned annular flange a' at its inner end, flange a' being provided with grooves a^2 to permit the escape of gas, the interior of flange a^2 being 65 square to receive and engage a washer hereinafter described. A tubular insulating lining B of fiber or similar material is provided and is cut away at b for the contact member hereinafter described.

Insulating member D prevents a shock to the user being located between the shell and metallic collar E, the latter being formed as shown to clamp member D and insulating member F to the outturned flange of the shell, said collar having an extension e threaded to engage threaded cap G, the latter having an opening g covering which is a mica disk g' , so that the interior of the device may be seen, the cap preventing the 80 escape of gases at the outer end of the plug but being readily applied and readily removed to give access to the interior of the plug for insertion of a new fuse.

At the center contact end of the plug I 85 provide inner insulating washer H preferably of fiber having apertures h h' for the legs of the center contact member hereinafter described, aperture h^2 for the screw and aperture h^3 for the fuse wire, the inner 90 washer being slightly spaced from the plug lining for the passage of gas.

Intermediate insulating washer K, preferably of fiber, is square and fits the opening in flange a^2 and is cut away at k k to permit 95 the passage of gas. Washer K has apertures k k' for the legs of the center contact member, aperture k^2 for the screw and aperture k^3 for the fuse wire.

Outer insulating washer M is preferably 100 of mica and engages the outer face of flange a^2 and has an elongated aperture m for said legs and the screw, said aperture having a side portion for passage of the fuse wire, the mica washer readily yielding to permit escape of the gas which passes between the plug lining and washer H, thence by portions k k and through grooves a^2 and thence between the flange a^2 and the mica washer M.

I also use a paper washer N to reinforce 110

the washer M, the paper washer having an aperture n with a side portion for the same purposes as the aperture of washer M.

The center contact member has a flat portion p , a central raised portion p' with a threaded aperture p^2 , a pair of legs p^3 p^4 and an aperture or hole p^4 for passage of the fuse wire, said raised portion fitting closely against washer N and reinforcing the latter and said legs passing through washers H, K, M and N to the position shown in dotted lines in Fig. 5 and then being clenched as shown in full lines in Fig. 5.

Binding screw R is threaded to engage the threading of aperture p^2 and holds one end of the fuse wire S in place, the head of the binding screw being wide enough to cover the hole p^4 in portion p and the binding screw being adjustable to permit the removal of the blown fuse wire and the insertion of and engagement with a new one.

Fuse wire S passes from the center contact through hole p^4 and through the appropriate apertures of washers N, M, K and H and is deflected at the insulating barrier T, extending thence into contact with contact T' where it is held by binding screw t, said contact T' having prongs t' t'' which are bent around the barrier to hold it in position, contact T⁸ passing through portion b and having prongs t^2 t^2 which are riveted to shell A, the riveting being covered by insulating member D.

In Fig. 12 I show an elongated form of plug having cap G, collar E', insulation D', shell A', washers M' and N', center contact member p^5 and binding screw R', all similar to the form of Fig. 1, the main difference being in the length of shell, this long form of shell being largely used in foreign countries and illustrates the great saving due to my invention because with my invention the plug may be refilled, thus avoiding the throwing away of expensive material.

In Fig. 12 I show another form of means to cover the hole for the passage of the fuse wire through the center contact member and for many purposes I prefer this means which comprises a standard screw head R² holding in place a washer p^6 which covers said hole.

What I claim is:

1. A refillable plug comprising a center contact; a shell; insulating material between the center contact and shell and provided with a passage separate from the opening for the center contact; and a fuse wire connected with said shell and extending through said passage and connected to said center contact.

2. A device of the character described comprising a shell; a center contact; a fuse wire connected to the center contact and a

plurality of washers insulating said contact from said shell, said center contact having lugs passing through said washers and holding them in position, and having a hole for the passage of the fuse wire.

3. A device of the character described comprising a shell; a contact fastened to said shell; and an insulating barrier supported by said contact.

4. A refillable plug having a metallic screw shell; a fuse wire; a terminal contact for connecting the fuse wire to said screw shell; and a metallic collar insulated from but fastened to, the screw shell; and a screw cap for engaging said collar for opening the plug to insert a new fuse.

5. A refillable plug having a center contact; a screw shell; a contact riveted to the screw shell, said screw shell forming the body of said plug and having an insulating lining within it; a collar insulated from, but connected to, said screw shell; and a cap engaging said collar.

6. A terminal contact for a refillable plug consisting of a washer with projecting lugs to hold it to the plug and with a screw-threaded aperture in its center and having a hole alongside of said center threaded aperture for the passage of a fuse wire; and a screw for fastening said wire to said washer.

7. A refillable fuse plug having a shell; a fiber ring near the top periphery of the shell; a fiber washer placed between the fiber ring and the top of the screw shell; a second insulating washer placed on top of first washer; a screw threaded collar holding the two washers in position; and a threaded cap to engage said threaded collar.

8. A refillable plug comprising a shell with an outturned flange at its top; insulating material above said flange; insulating material below said flange; a metallic collar holding said insulating material in place and having a threaded extension; and a threaded cap to engage said threaded extension.

9. A refillable plug comprising a shell; a center contact having legs and a binding screw; a fuse connected to said center contact outside of the plug; and material insulating said center contact from said shell, said material including an inner washer apertured for said legs, said screw and said wire; an intermediate washer similarly apertured; and an outer washer similarly apertured, said legs passing through said washers and holding said insulating material in place.

RALPH A. SCHOENBERG,
Now by judicial change of name Ralph A.
Belmont.
